(57) **CLAIM**

The ornamental design for an artificial intelligence headphone with optical integrated glasses for augmented reality, as shown and described.

DESCRIPTION

FIG. 1 is a front top perspective view of an artificial intelligence headphone with optical integrated glasses for augmented reality showing my new design;

FIG. 2 is a rear bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

In the figures, shading represents contour and not any particular color, and the broken lines shown in the drawings are for the purpose of illustrating portions of the artificial intelligence headphone with optical integrated glasses for augmented reality that form no part of the claimed design.
